UNITED STATES PATENT OFFICE.

JOSEPHUS HOOPER, OF LOUISVILLE, KENTUCKY.

WINDOW-BEAD FASTENER.

SPECIFICATION forming part of Letters Patent No. 443,852, dated December 30, 1890.

Application filed April 8, 1890. Serial No. 347,014. (No model.)

To all whom it may concern:

Be it known that I, JOSEPHUS HOOPER, a citizen of the United States, residing at Louisville, in the county of Jefferson and State of Kentucky, have invented certain new and useful Improvements in Window-Frames; and I do hereby declare the following to be a full, clear, and exact description of the invention, such as will enable others skilled in the art to which

it appertains to make and use the same.

My invention has reference to the construction of window-frames, and relates more especially to the means whereby the sashes are held and guided in place. Its object is to provide means whereby the sashes may be easily taken out of the frames for repairs or swung into the room, so as to be cleaned from the interior, thereby effecting a great saving of time in the cleaning of the windows, as well as avoiding all danger of the accidents so commonly resulting from one side of the sashes being accessible only from the exterior; and it consists in the means hereinafter described and claimed for securing the sash-holding strips in place, so that they may be readily detached and replaced without the use of nails or screws and without the aid of special tools, thereby permitting the sashes to be pulled down and swung into the room, where both sides may be brought within easy reach and conveniently and safely cleaned, repaired, painted, &c.

In the accompanying drawings, Figure 1 is a fragmentary perspective view of a window-frame, the sash-holding plates being removed, so as to expose to view the locking-plates. Fig. 2 is a transverse sectional detail through the sashes, strips, and frame. Fig. 3 is a similar view, the sashes and the interior and parting strips being removed. Fig. 4 is a sectional detail lengthwise through one of the side strips, showing the fastening or locking devices. Fig. 5 is a plan view of one of the side strips, and Fig. 6 is a perspective of the locking-plate.

A A are the usual top, side, and bottom pieces of the ordinary rectangular window-frame.

B is the outer, C the inner, and D the parting, strip. The outer strip there is no need to remove, and it is nailed or screwed onto the frame in the ordinary way. It may, if pre-

ferred, however, be fastened like the others. The inner and parting strips C D, instead of being also fastened to the frame in this manner, as is generally the case, are removably secured thereto, so that they may be readily detached and taken entirely out, leaving the sides of the frame unobstructed and permitting the sashes to be removed from the interior.

E are the sashes.

The simplest and most convenient way which I have so far devised for doing this is represented in the drawings, and is as follows: In the top, bottom, and side pieces of the frame where the strips are to come I cut one or more (preferably two) shallow mortises a. I cover each of these mortises by a plate b, set into the rabbeted edges of the mortise, the plates being provided with key-hole slots and secured in place by screws, as shown, or nails. Into the strips, at points which correspond with the mortises when the strips are in place, headed pins or screws d are seated, the heads projecting from the face of the strip a distance about equal to the thickness of the plates b. In order to fasten the strips in place, it is only necessary to adjust them so that the heads of the screws will pass through the larger part of the key-hole slot, when by pushing the strip endwise the shank of the screw passes into the narrow part of the slot, and the head is effectually confined beneath the plate, thus firmly securing the strip to its seat on the frame. It will of course be understood that a short mortise is cut in the side of the frame to receive the entering end of the strip. Thus secured, the strips cannot be loosened or removed except by first sliding them endwise till the screw-heads can pass through the large part of the slot in the plate b. In raising and lowering the sashes there is nothing to force the upper or lower horizontal strips endwise. There is therefore no need of any provision against endwise movement in these strips. In the vertical side strips, however, the friction of the sashes, as they move up and down, would probably carry the strips with them the length of the mortise in the end of the adjacent frame-piece. As this would render these strips liable to fall out or be detached unintentionally when the screw-heads coincide

with the head of the slots, I provide a means to hold these vertical strips against longitudinal movement. A convenient device for this purpose is the spring-catch *e*, consisting, preferably, of a wire bent into the form shown in Fig. 5, one end passing clear through a slot in the strip and adapted to enter the large part of the key-hole slot in the plate *b*, and the other end secured to the outer side of the strip by having a short tang driven into the strip and being held down by a staple *f*. In order to fasten the strip into place, the screw-head is passed through the slot and the strip moved endwise till the shank of the screw *g* passes well into the narrow part of the slot, when the catch *e* snaps into the opposite end of the slot and the strip is effectually held against longitudinal movement in either direction. In order to remove the strip, the catch must be withdrawn before the strip can be slid into a position where the screw-heads will pass out. The end of the wire turned back upon itself, as shown in Fig. 5, forms a convenient knob for this purpose.

25 In the drawings I have shown the parting strip *D* as set into a groove in the bottom piece of the frame. This, however, is not necessary, as it may be seated on the flat top as the inner strip *C* is set. As before stated, 30 the outer strip may be secured in the same manner as the others; but it is preferably fixed. It may be found unnecessary to make all the inner strips removable; but it is deemed best to do so.

35 Having thus described my invention, what I claim, and desire to secure by Letters Patent, is—

1. The combination of a window-frame, a sash-holding strip, a headed pin on the under side of the strip, a mortise in the frame, a plate covering the mortise and having a key-hole slot therein, and an auxiliary catch to hold the strip against endwise movement, substantially as described.

2. In a window-frame, the combination of the sash-holding strip, the mortise *a* in the frame, the plate *b*, covering the mortise, the key-hole slot *c* in the plate, the headed pin or screw in the under side of the strip, and a spring-catch to hold the pin in the narrow part of the slot, substantially as described.

3. In a window-frame, the combination of the sash-holding strip, the mortise *a* in the frame, the plate *b*, covering the mortise, the key-hole slot *c* in the plate, the headed pin or screw in the under side of the strip, and the spring-catch secured upon the outer side of the strip and having its end projecting through the strip alongside of the pin, substantially as described.

4. In a window-frame, the combination of the sash-holding strip, the mortise *a* in the frame, the plate *b*, covering the mortise, the key-hole slot *c* in the plate, the headed pin or screw in the under side of the strip, and the spring-catch projecting inward from the strip and having a knob or thumb-piece on the outer side, substantially as described.

In testimony whereof I affix my signature in presence of two witnesses.

JOSEPHUS HOOPER.
